[57] CLAIM

The ornamental design for a sundae machine, substantially as shown and described.

DESCRIPTION

FIG. 1 is a front elevational view of a sundae machine showing our new design;

FIG. 2 is a side elevational view of the sundae machine of FIG. 1, viewed from the right side;

FIG. 3 is a side elevational view of the sundae machine of FIG. 1, viewed from the left side;

FIG. 4 is a rear elevational view of the sundae machine of FIG. 1;

FIG. 5 is a plan view of the sundae machine of FIG. 1; and

FIG. 6 is a bottom view of the sundae machine of FIG. 1.

*Fig. 1.**Fig. 2**Fig. 4.*

*Fig. 5.**Fig. 6.*
